I claim the ornamental design for a shelving unit and components, as shown and described.

DESCRIPTION

FIG. 1A is a perspective view of a first component of the shelving unit.

FIG. 1B is a right view of the first component of the shelving unit.

FIG. 1C is a left view of the first component of the shelving unit.

FIG. 1D is a front view of the first component of the shelving unit.

FIG. 1E is a rear view of the first component of the shelving unit.

FIG. 1F is a top view of the first component of the shelving unit.

FIG. 1G is a bottom view of the first component of the shelving unit.

FIG. 2A is a perspective view of a second component of the shelving unit.

FIG. 2B is a right view of the second component of the shelving unit.

FIG. 2C is a left view of the second component of the shelving unit.

FIG. 2D is a front view of the second component of the shelving unit.

FIG. 2E is a rear view of the second component of the shelving unit.

FIG. 2F is a top view of the second component of the shelving unit.

FIG. 2G is a bottom view of the second component of the shelving unit.

FIG. 3A is a perspective view of a third component of the shelving unit.

FIG. 3B is a right view of the third component of the shelving unit.

FIG. 3C is a left view of the third component of the shelving unit.

FIG. 3D is a front view of the third component of the shelving unit.

FIG. 3E is a rear view of the third component of the shelving unit.

FIG. 3F is a top view of the third component of the shelving unit.

FIG. 3G is a bottom view of the third component of the shelving unit.

FIG. 4A is a perspective view of a fourth component of the shelving unit.

FIG. 4B is a right view of the fourth component of the shelving unit.

FIG. 4C is a left view of the fourth component of the shelving unit.

FIG. 4D is a front view of the fourth component of the shelving unit.

FIG. 4E is a rear view of the fourth component of the shelving unit.

FIG. 4F is a top view of the fourth component of the shelving unit.

FIG. 4G is a bottom view of the fourth component of the shelving unit.

FIG. 5A is a perspective view of a fifth component of the shelving unit.

FIG. 5B is a right view of the fifth component of the shelving unit.

FIG. 5C is a left view of the fifth component of the shelving unit.

FIG. 5D is a front view of the fifth component of the shelving unit.

FIG. 5E is a rear view of the fifth component of the shelving unit of the shelving unit.

FIG. 5F is a top view of the fifth component of the shelving unit.

FIG. 5G is a bottom view of the fifth component of the shelving unit.

FIG. 6A is a perspective view of a sixth component of the shelving unit.

FIG. 6B is a right view of the sixth component of the shelving unit.

FIG. 6C is a left view of the sixth component of the shelving unit.

FIG. 6D is a front view of the sixth component of the shelving unit.

FIG. 6E is a rear view of the sixth component of the shelving unit.

FIG. 6F is a top view of the sixth component of the shelving unit.

FIG. 6G is a bottom view of the sixth component of the shelving unit.

FIG. 7A is a perspective view of a seventh component of the shelving unit.

FIG. 7B is a right view of the seventh component of the shelving unit.

FIG. 7C is a left view of the seventh component of the shelving unit.

FIG. 7D is a front view of the seventh component of the shelving unit.

FIG. 7E is a rear view of the seventh component of the shelving unit.

FIG. 7F is a top view of the seventh component of the shelving unit.

FIG. 7G is a bottom view of the seventh component of the shelving unit.

FIG. 8A is a perspective view of an eighth component of the shelving unit.

FIG. 8B is a right view of the eighth component of the shelving unit.

FIG. 8C is a left view of the eighth component of the shelving unit.

FIG. 8D is a front view of the eighth component of the shelving unit.

FIG. 8E is a rear view of the eighth component of the shelving unit.

FIG. 8F is a top view of the eighth component of the shelving unit.

FIG. 8G is a bottom view of the eighth component of the shelving unit.

FIG. 9A is a perspective view of a first alternate configuration of shelving unit.

FIG. 9B is a front view thereof.

FIG. 9C is a left view thereof.

FIG. 9D is a right view thereof.

FIG. 9E is a top view thereof.

FIG. 9F is a bottom view thereof.

FIG. 9G is a rear view thereof.

FIG. 10A is a perspective view of a second alternate configuration of shelving unit.

FIG. 10B is a front view thereof.

FIG. 10C is a left view thereof.

FIG. 10D is a right view thereof.

FIG. 10E is a top view thereof.

FIG. 10F is a bottom view thereof.

FIG. 10G is a rear view thereof.

FIG. 11A is a perspective view of a third alternate configuration of shelving unit.

FIG. 11B is a front view thereof.

FIG. 11C is a left view thereof.

FIG. 11D is a right view thereof.

FIG. 11E is a top view thereof.

FIG. 11F is a bottom view thereof.

FIG. 11G is a rear view thereof.

FIG. 12A is a perspective view of a fourth alternate configuration of shelving unit.

FIG. 12B is a front view thereof.

FIG. 12C is a left view thereof.

FIG. 12D is a right view thereof.

FIG. 12E is a top view thereof.

FIG. 12F is a bottom view thereof; and,

FIG. 12G is a rear view thereof.

The figures show various views of each component of the shelving unit. The broken lines in the various views depict the boundaries of the claim and form no part of the claim.
